US00D881233S

(12) **United States Design Patent** (10) **Patent No.:** **US D881,233 S**
Maguire et al. (45) **Date of Patent:** **** Apr. 14, 2020**

(54) **DISPLAY SCREEN OR PORTION THEREOF
WITH GRAPHICAL USER INTERFACE**

(71) Applicant: **Knowmadics, Inc.**, Herndon, VA (US)

(72) Inventors: **Paul Maguire**, Manassas, VA (US);
Charles Corcoran, Duluth, GA (US);
Cody Ostrum, Leesburg, VA (US);
Claire Ostrum, Leesburg, VA (US);
Tim Do, Ashburn, VA (US)

(73) Assignee: **Knowmadics, Inc.**, Herndon, VA (US)

(**) Term: **15 Years**

(21) Appl. No.: **29/650,172**

(22) Filed: **Jun. 5, 2018**

Related U.S. Application Data

(63) Continuation of application No. 15/691,785, filed on Aug. 31, 2017, which is a continuation of application No. 14/561,564, filed on Dec. 5, 2014, now Pat. No. 9,807,183.

(57)

CLAIM

The ornamental design for a display screen or portion thereof with graphical user interface, as shown and described.

DESCRIPTION

The sole FIGURE shows a display screen or portion thereof with graphical user interface showing our new design. The dashed chain lines illustrate a display screen or portion thereof, and form no part of the claimed design. The other broken lines in the figures show surrounding environment or portions of the graphical user interface that form no part of the claimed design.

1 Claim, 1 Drawing Sheet
